UNITED STATES PATENT OFFICE.

CHESTER D. AINSWORTH, OF WOLLASTON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

ELECTRICALLY-OPERATED SWITCH.

Application filed June 28, 1921. Serial No. 481,125.

This invention relates to electric switches and particularly to remotely-controlled switches especially adapted to control the starting and running of electric motors; and has for its object to improve the construction and operation of electric switches of the type above set forth.

Figs. 1 and 2 are front and side view respectively of a switch embodying the invention.

Fig. 3 is a plan view of the switch with the cover removed and illustrating more particularly the arrangements for the circuit leads and fuses.

Fig. 4 is a view along line 4—4 of Fig. 5.

Fig. 5 is a sectional elevation along line 5—5 of Fig. 2.

Fig. 6 is a sectional view along line 6—6 of Fig. 5.

Fig. 7 is a front view of the switch with the casing partially broken away to expose the movable switch member in switch-open position.

Figs. 8 and 9 are end and side views respectively of the closing and holding magnet core, with the coil removed.

Fig. 10 is a circuit diagram illustrating the connections between the circuit leads, the holding coil and a remote control switch.

As here shown the switch embodying the invention includes the enclosing receptacle comprising the upper rectangular open top and bottom casing 10 closed at the top by the cover 11 removably secured in place by the screws 12, and closed at the bottom by the oil receptacle 13 which is secured removably to the said casing by the bolts 14. The switch mechanism and the stationary and movable switch members is adapted to be contained in the lower part of said casing 10 and immersed in the oil in said receptacle and fuses are adapted to be contained in the upper part of said casing and rendered accessible for renewal by removal of the cover 11.

Ears 15 are struck out from the lower edge of the front and rear walls of said casing to form a shelf on which the plate 16 is supported. Said plate is formed preferably of insulating material, as porcelain, and, preferably, is a close fit within the casing whereby substantially to isolate the upper and lower portions of the casing and separate the chambers containing the switch

mechanisms and the fuses and circuit leads. 55

The upper face of said plate is provided with spring fuse clips 17 and 18 spaced and arranged to receive the tubular fuses 19 through which connection may be established between the line and the stationary 60 switch members. One set of fuse clips, as 17, is provided with binding screws 20 to which motor leads may be secured; and the motor leads may enter the casing through a conduit inserted through, say, the aperture 65 21 in the upper part of the casing.

Said plate is formed with the barriers 22 disposed between the tubular fuses. Pillars 23 rise above the upper face of said plate and screws 24 and 24^a extend therethrough 70 adapted to connect the switch closing and holding coil with leads extended to a remote control switch; and said leads may enter the casing through, say, the aperture 25.

The under side of said plate 16 is formed 75 with two recesses 26 and 27 and separated by the raised barrier 28; and said recesses are adapted to receive the stationary switch members 29 and 30. The particular switch here chosen to illustrate the invention is 80 adapted to control a three phase motor and consequently three sets of stationary switch members are illustrated. The same construction, however, will be employed for switches adapted to control circuits of different phases. Said stationary switch members are formed of resilient strips of metal, having their upper ends reflexed outwardly to form the foot-portions 29^a and 30^a which are received in said recesses 26 and 27 respectively and by which said switch members are secured to said plate 16. Screws 31 serve to secure said switch-members 29 to said plate 16 and also to connect them electrically to the fuse clips 18. Screws 32 to 95 serve to secure said switch-members 30 to said plate 16 and extend through said plate and serve as binding means arranged to receive line leads which may be introduced into the upper part of the casing through the aperture 33. Said switch-members depend downwardly into the oil in the oil receptacle and, in switch-open position, are, preferably, substantially parallel. The lower ends 29^b and 30^b of said members are 100 reflexed outwardly; and reversible and interchangeable contact members 34 are removably secured by suitable means, as screws 35,

to said reflexed ends. An insulating pin 36 having an enlarged body portion 36^a is loosely received in aligned apertures in each set of switch members and serve as spacers 5 by which to hold the switch members of each set a uniform distance apart and provide practically simultaneous closing and opening of the circuit in which said switch-members are included. The reduced portions of said 10 pins extend beyond said switch members a distance in excess of the extent of movement of said members when the bridging members, hereinafter to be described, are moved there-between to close the circuit controlled by the 15 switch whereby said pins will be retained in position without the necessity for especial retaining means.

A single coil 40 is employed to effect the 20 operation of the switch and the coil is arranged to be energized to close the switch and remain energized to hold the switch and be de-energized to effect the opening of the switch.

Said coil 40 is disposed upon and supported 25 by the leg 41 of the U-shaped magnetic structure or core having a second leg 42 and the integral connecting portion 43 and formed of a plurality of assembled laminæ. Said core is received in the recess 44 of the plate 30 16 and two sets of angle members 45 and 46 are disposed on opposite sides of and secured to said core and also to said plate whereby to secure said core in position. An angle member 47 is secured to said leg 42 on the lower 35 portion of its inner face and the leg 47^a of said member extends below and forms a support for said coil 40 and also serves to maintain the coil in place on the core.

The movable switch member includes the 40 bar or armature 48 formed of a plurality of assembled laminæ and is adapted to be pivoted to one of the legs of the core, as the leg 42, and attracted to a position in engagement with the lower faces of both legs of 45 the core to close the switch. An end of said armature 48 is formed with a vertically elongated slot 49 therein and a pivot pin 50 is passed through said slot and fixed in lateral extensions of the leg 42 of the core, as 50 the angle members 51 and 52 secured to opposite faces of said leg 42 and depending therebelow. The loose pivotal connection between the core and armature is highly desirable in that it permits the pivoting of 55 the armature about said pin to close the switch and the armature is thereafter drawn into close contact with the ends of the legs of the core whereby the reluctance of the magnetic circuit is made low and the coil 40 is 60 enabled to hold the switch closed with a low power consumption.

It will be noted that said angle members 45, 46, 47, 51, and 52 are identical and interchangeable one in place of another whereby 65 to effect economy in manufacture.

Shading coils 53 and 54 may be applied to the end faces of the legs 41 and 42 of the core, if desired, to reduce noise and assist in holding the armature in attracted position.

The movable switch member also includes 70 the bar 55, which may be slightly flexible, if desired; and said bar is secured to the lower face of the armature 48 by the screws 56. Said bar is formed with the rear upwardly reflexed end-portion 57 adapted to engage the 75 leg 42 of the core and limit the movement of the movable switch members in a switch-opening direction. The forward end of said bar is forked to provide two arms or branches 58 and 59; and an insulating bar 80 60 is secured to said arms. Movable contact members 61 are carried by and spaced along said bar and secured thereto by the bolts 62; and said contact members are formed with the downwardly and outwardly reflexed end- 85 portions 61^a adapted to make contact with the stationary contact members. Due to the wedge shape of said movable contact members, said members will be forced between and cause the stationary contact members to 90 spread while in contact therewith and thereby to provide a wiping or self-cleaning contact.

It is obvious that when said coil 40 is effectively energized the armature 48 will be 95 attracted and the movable contact members will be moved upwardly to engage and bridge the stationary contact members and that the movable switch member will remain in closed position until said coil 40 is de- 100 energized.

The switch above described is adapted to be controlled by a remote control switch having closing and opening positions and usually having a button to be depressed to cause the closing of the switch and a separate button to be depressed to cause the opening of the switch although the arrangement may vary somewhat in specific instances.

Fig. 10 illustrates diagrammatically the 110 connections between the switch and the line and motor circuits and between the switch and the remote control switch. The remote control switch comprises the "closing" bridging member *a* adapted to bridge and connect 115 the stationary contact members *b* and *c* but arranged normally to be free therefrom until depressed. The "opening" bridging member *d* is arranged normally to bridge the stationary contact members *c* and *e* until 120 depressed to break contact therewith. The act of depressing the closing switch *a* is arranged to complete the circuit through the holding coil 40 and the circuit through said coil is arranged thereafter to be maintained 125 closed at the switch itself. The act of depressing the opening switch *d* is arranged to break the holding circuit and de-energize the holding coil 40 and cause the switch to open; and the arrangements are such that 130

the closing switch *a* must again be depressed before the switch can again be closed.

In a switch of the type above set forth, it has been more or less common practice to provide an auxiliary switch structure independent of the main switch structure but operated synchronously therewith to control the circuit for the closing and holding coil. It is an object of this invention to utilize a part of the main switch structure to accomplish the results heretofore accomplished with auxiliary switches. To this end a flexible lead 70 is extended from the fixed post 24 of the supporting plate 16 to and connected with the bolt 62 which secures say an outermost movable contact member 61 to the insulating bar 60; and consequently said post 24 will be electrically connected with said movable contact member. Said lead 70 is arranged with sufficient length and flexibility to permit free movement of the movable switch member. The contact member *c* of the remote control switch is connected through the conductor *f* to the post 24 and the contact member *b* to a stationary switch member 32 through the conductor *g*. The contact member *e* is connected with the post 24 through the conductor *h*; and the coil 40 is connected between said post 24 and one of the stationary switch members 32 other than the one to which the remote control switch member *b* is connected.

With the arrangement above set forth it will be seen that when the "closing" bridging member *a* is depressed, and with the switch in open position, a circuit will be established between the bridging members *a* and *d* and the closing coil 40 and the outer leads of the line circuit and the switch will be moved into closed position. When the switch is moved into closed position, the circuit through the coil 40 is also established through the lead 70 and the movable contact member 61 connected therewith; and the coil will remain energized when the "closing" bridging member *a* is released from engagement with its contact members. When the "opening" bridging member *d* is depressed the circuit through said lead 70 is broken and the coil 40 becomes de-energized and consequently the switch opens and can be closed only by again depressing the "closing" bridging member *a*.

It is obvious that the structure herein described for the purpose of illustrating the invention may be modified without departing from the spirit of the invention.

I claim:

1. An electric switch having the combination of a substantially horizontal insulating supporting plate, two relatively flexible insulated opposed stationary switch members comprising opposite terminals of the switch secured to and depending from said plate and having lower divergent contact termi-

nals, a vertically-movable switch-member including an arm, a support depending from said plate to which said arm is pivoted, a wedge-shaped insulated contact member carried by said arm and comprising a flat plate having downwardly reflexed end-portions, means arranged to force said wedge shaped contact member in between and thereby bridge and electrically connect the divergent contact terminals of said flexible stationary switch members, and an oil receptacle depending from said supporting plate and enclosing the aforesaid members, said supporting plate comprising a cover for said oil receptacle.

2. An electric switch having the combination of a substantially horizontal insulating supporting plate, two relatively flexible opposed and insulated stationary switch members secured to and depending from said plate and having lower divergent contact terminals, a vertically-movable switch-member including an arm, a support depending from said plate to which said arm is pivoted, a wedge-shaped insulated contact member carried by said arm and arranged to be moved upwardly between and electrically connect the divergent contact terminals of said stationary switch members, electrical means secured to and depending from said plate arranged to operate said movable switch member, said electrical means including a U-shaped electromagnet and said arm-support, and an armature therefor connected with said movable switch-member, and an oil receptacle depending from said supporting plate and enclosing the aforesaid members, said supporting plate comprising a cover for said receptacle.

3. An electric switch having the combination of an enclosing casing, an insulating supporting plate disposed within said casing, two opposed and spaced-apart, resilient stationary switch-members dependingly secured to said plate and having their lower ends divergent, a movable switch member including an arm pivotally carried by said plate, and a contact member having divergent end-portions arranged to be moved into position between and spread outwardly and electrically connect said stationary switch members, an insulating member disposed between said divergent end-portions and insulatingly connecting said contact member and arm, and electrical means to operate said movable switch member, said enclosing casing including an oil receptacle depending below said supporting plate.

4. An electric switch having the combination of an insulating supporting plate, two spaced-apart resilient stationary switch members secured to and depending below said plate and having divergent end-portions, contact-members removably secured to said end-portions, an insulating spacing member

- disposed between and loosely carried by said switch member intermediate the ends thereof to maintain said switch members spaced apart, a movable switch member including a pivoted arm, an insulating member carried on the end thereof, a contact member having downwardly and outwardly divergent arms secured to said insulating member arranged to be moved upwardly between and bridge said stationary switch members, and electrical means dependingly secured to said supporting plate to operate said movable switch member.
5. An electric switch having the combination of an insulating supporting plate, groups of stationary switch members secured to and depending below said supporting plate, each group comprising two resilient spaced-apart members having divergent lower end-portions, a movable switch-member including an arm pivotally carried by said supporting plate and having two spaced branches, an insulating bar secured to and between said branches, and a plurality of insulated wedge-shaped contact members carried by said bar arranged each to engage and bridge the stationary switch members of each group, and electrical means to operate said movable switch member.
6. An electric switch having electric switch-operating means for closing and holding closed the switch including a magnetic core having two legs, an energizing coil disposed on one of said legs, an armature loosely pivoted at but normally free from direct engagement with said other leg arranged to be attracted into a position in contact with the end faces of both legs, and relatively movable stationary and movable contact members arranged to be moved into and away from engagement by said armature.
7. An electric switch including electrical switch-operating mechanism for closing and holding closed the switch including a magnetic core having two legs, an energizing coil disposed on one of said legs, two supporting members secured to opposite faces of said other leg and extended beyond the end thereof, a pivot pin extended between and secured in the portions of said supporting members, an armature having a vertically elongated slot therein in which said pivot pin is loosely received, whereby said armature may be moved and held in direct contact with both legs, and yielding stationary and movable switch members arranged to be held in engagement by said armature.
8. An electric switch including a supporting plate, electric switch-operating-means including a magnetic core having two legs, an energizing coil disposed on one of said legs, attaching members secured to said core and to said supporting plate, supporting members secured to opposite sides of said other leg and extended therebeyond, a pivot pin extended between and secured to the extended portions of said supporting members, an armature disposed between said supporting members having a pivot hole therethrough in which said pivot pin is received, said supporting and attaching members being identical and interchangeable, and stationary and movable switch members arranged to be moved into and away from engagement by said armature.
9. An electric switch including electrical switch-operating means including a magnetic core having two legs, an energizing coil loosely disposed on one of said legs, a member secured to and extended from said second leg and terminated short of said coil-leg arranged to engage and support said coil in position, an armature pivoted to said second leg, and movable and stationary switch members arranged to be moved into and away from engagement by said armature.
10. An electric switch including a supporting plate, electrical switch-operating means including a magnetic core secured to said plate and having two depending legs, an energizing coil disposed on one of said legs, an armature pivoted to the lower end of said second leg and extended across said other leg, a bar secured to said armature and extended therebeyond on one end, insulated contact members carried by said extended end of said bar, and said bar having a projection extended upwardly beyond the pivoted end of said armature and arranged to engage the second leg of said core and limit the downward movement of said armature, and stationary switch members dependingly carried by said plate arranged to be engaged by said contact members.
11. An electric switch including a receptacle, an insulating supporting plate disposed in said receptacle, electrical switch operating means including a magnetic core dependingly secured to said supporting plate, an energizing coil disposed on one leg of said core, supporting members secured on opposite sides of said second leg and extended therebeyond, a pivot pin extended between and secured in the extended portions of said supporting members, an armature disposed between said supporting members having a vertically-elongated slot in one end in which said pivot pin is loosely received, a bar secured to said armature and extended therebeyond and provided with two branches, an insulating bar extended between and carried by said branches, insulated contact members having downwardly and outwardly divergent end portions carried by said bar, a plurality of groups of stationary switch members dependingly secured to said supporting plate, each group comprising two spaced resilient switch members having divergent lower end-portions arranged to be engaged by said contact members.

engaged and electrically bridged by said contact members, said bar extended upwardly beyond the pivotal end of said armature and arranged to engage said second leg of the magnetic core and limit the downward movement of said armature.

12. An electric switch comprising the combination of an insulating supporting plate, pairs of stationary switch members depending therefrom, each pair comprising a pair of relatively long and flexible opposed and insulated arms secured to and depending below said supporting plate and having divergent lower end-ports, an arm pivotally supported below said switch members, an insulating bar carried by said arm, a plurality of wedge-shaped bridging members carried in spaced and insulated relation on said insulating bar, and electrical operating mechanism comprising an electromagnet core carried by and depending below said supporting plate, said core having two poles arranged above and along the length of said arm, an armature carried by said arm and arranged along the length thereof, and pivotal supporting means for said arm and armature.

13. An electric switch having the combination of an enclosing casing including a removable oil receptacle, an insulating supporting plate disposed within and secured to said casing and comprising a cover for said oil receptacle, stationary switch members comprising a pair of opposed insulated approximately parallel and relatively long and flexible arms carried by and depending below said plate and comprising opposite terminals of the switch, said arms having divergent removable contact terminals, and a stationary switch member comprising a bracket carried by and depending below said supporting plate, an arm pivoted to

said bracket and extended below the level of said stationary switch members, and a wedge-shaped insulated contact member 45 carried by said arm having reflexed downwardly and outwardly dependent end-ports forming contact surfaces and arranged to be moved forcibly upward between the contact terminals of said stationary switch members and electrically connect them and thereby complete the circuit through the switch.

14. An electric switch having the combination of an enclosing casing, an insulating supporting plate disposed within and secured to said casing intermediate the height thereof, stationary switch members comprising a pair of opposed insulated approximately parallel and relatively long 60 and flexible arms carried by and depending below said plate and comprising opposite terminals of the switch, said arms having divergent removable contact terminals, and a movable switch member comprising 65 a bracket carried by and depending below said supporting plate, an arm pivoted to said bracket and extended below the level of said stationary switch members, and a wedge-shaped insulated contact member 70 comprising a plate having downwardly reflexed end-ports carried by said arm and arranged to be moved forcibly upward between the contact terminals of said stationary switch members and electrically 75 connect them and means to restrict the extent of upward movement of said wedge-shaped contact member, the lower portion of said enclosing casing comprising a receptacle adapted to contain oil in which the 80 switch-members are immersed.

In testimony whereof, I have signed my name to this specification,

CHESTER D. AINSWORTH.
